United States Patent Office

Des. 187,905
Patented May 17, 1960

187,905

LIQUID DISPENSING FAUCET

Harold O. Seltsam, Rocky River, Ohio, assignor to Tomlinson Industries, Inc., Cleveland, Ohio, a corporation of Ohio

Application July 23, 1958, Serial No. 51,908

Term of patent 14 years

(Cl. D2—3)

Fig. 1

Fig. 2

Fig. 3

Fig. 4

Fig. 1 is a top plan view of my liquid dispensing faucet; Fig. 2 is a front view in elevation; Fig. 3 is a side view; and

Fig. 4 is a bottom view thereof.

The dominant features of the design reside in the portions shown in the full lines and described in the claim.

I claim:

The ornamental design for a liquid dispensing faucet, as shown and described.
